Inventor:

Geo. Metcalf
By his atty. R. D. Smith

UNITED STATES PATENT OFFICE.

GEORGE METCALF, OF SOMONAUK, ILLINOIS.

IMPROVEMENT IN WIND-WHEELS.

Specification forming part of Letters Patent No. 142,256, dated August 26, 1873; application filed July 11, 1873.

To all whom it may concern:

Be it known that I, GEORGE METCALF, of Somonauk, in the county of De Kalb and State of Illinois, have invented a new and useful Improvement in Wind-Wheels; and I do hereby declare the following to be a full, clear, and exact description of the same, reference being had to the accompanying drawings, in which—

Figure 1 is a perspective elevation of my machine. Fig. 2 is a plan of the same.

This invention relates to an improvement in wind-wheels, whereby the mounting and supporting of said wheels are made cheaper, more convenient, and more durable than heretofore; and it consists, first, in mounting the wheel at the top of and within a revolving frame or tower, the lower end of which extends down into a permanent frame-work or structure, with friction-wheels set in the top of said frame-work, and a pivot-step at the bottom; second, in a method of arranging an automatic governor.

That others may fully understand my improvement, I will particularly describe it.

The wheel A is constructed with oblique radial vanes or wings, permanently set and fastened to the wheel-hub at their inner ends, and to a rim or any proper encircling device at their outer ends. This wheel is not governed by adjusting the vanes to a greater or less obliquity to the wind, but by turning the wheel itself more or less edge to the wind, and thereby avoiding the complication of parts and numerous joints necessary to a separate movement of each vane. The wheel-shaft is provided with a crank, and has its bearings in two upright posts or standards, B B, which form portions of a revolving frame or tower, which extends downward within a permanent structure, C, as far as may be required to secure the necessary stiffness and strength. The wheel A is located between the said posts and directly above the step D. The frame or tower B rests at its bottom upon a tubular step, D, upon which it turns freely; and opposite the top of the structure C it is provided with a cylindrical portion or frame, E, to traverse three or more friction-rollers, F, set in bearings at the top of said structure C, so that the tower B will, to a very great extent,

be relieved from friction during its revolution, even under the lateral pressure of the wind against the wheel A. The greater the distance between the step D and the rollers F, in proportion to the whole height of the tower B, the less will be the frictional resistance.

The wheel A, being located between its shaft-bearings, will be supported without unequal friction therein; and being located also in the axis of the revolution of the tower B, it is perfectly balanced as to the wind-pressure upon it, and presents no resistance to its control by the tail vane.

The crank-rod or pitman G extends downward from the wheel-shaft crank and through the tubular step D, so that its working is not impeded by the revolution of the tower B. A swivel-joint must, of course, be inserted in said rod somewhere between the crank and its connection with the pump which is actuated by it. To govern the wheel, a small vane, H, is attached to the tower B, parallel with the plane of revolution of said wheel, and this small vane exerts a constant tendency to turn said wheel edge to the wind. The steering-vane I is hinged to the revolving tower B, and is jointed by means of a flexible connection, J, to an arm, K, permanently secured to said tower. The flexible connection J is sufficiently long to permit the vane I to swing around parallel with vane H, and the wheel A may then move edge to the wind. The tendency of the vane I to swing around into the position named is controlled by a weight, L, suspended from said connection J; and it is evident that the wheel A will be controlled and held face to the wind exactly in the proportion of the gravity of said weight to the moving force of the wind.

To cause the wheel A to stop at any time, it is only necessary to raise the weight L by the cord M or other artificial means, when the wheel will immediately swing edge to the wind, and will come to rest. In order to render a comparatively light weight sufficient for this purpose, I place the weight L at the end of an arm or lever, N, and may also make it adjustable thereon, so as to be able to vary the power of the governor in proportion to the work to be done.

Having now described my invention, what I claim as new is—

1. The revolving tower B, constructed substantially as described, to support the wheel A between its shaft-bearings and above the step D, combined with the surrounding and supporting frame-work C, substantially as set forth.

2. In combination with the tower B, supporting the wheel A at its top between the shaft-bearings, and the surrounding and supporting frame-work or structure C, the step

D and friction-rollers F, to enable said tower to revolve with freedom.

3. In combination with the wheel A, steady vane H, and hinged vane I, the flexible connection J, arm K, lever N, and weight L, all arranged substantially as set forth.

In testimony that I claim the above as my invention witness my hand.

GEO. METCALF.
